UNITED STATES PATENT OFFICE

162,596

SIGN

Charles E. Trame, Lima, Ohio, assignor to International Harvester Company, a corporation of New Jersey

Application October 28, 1950, Serial No. 12,768

Term of patent 7 years

(Cl. D1—12)

To all whom it may concern:

Be it known, that I, Charles E. Trame, a citizen of the United States, residing in Lima, in the county of Allen and State of Ohio, have invented a new, original, and ornamental Design for a Sign, of which the following is a specification, reference being had to the accompanying drawings, forming part thereof, in which:

Fig. 1 is a perspective view taken from one side of a sign showing my new design, the opposite side being identical;

Fig. 2 is a top plan view; and

Fig. 3 is an end elevational view.

I claim:

The ornamental design for a sign, as shown and described.

CHARLES E. TRAME.
